TUYÈRE BLOCK

Application filed December 10, 1930. Serial No. 501,253.

This invention relates to tuyère blocks, and more particularly to tuyère blocks for automatic stokers of the underfeed type.

In underfeed stokers the fuel is usually delivered through openings in the front wall of a furnace into troughs or retorts provided with air admitting tuyère blocks along their upper margins. Air under pressure flows from an air chamber beneath the retorts through openings in the tuyère blocks into the fuel bed. The retorts usually slope downwardly toward an ash dump at the rear of the furnace, where the incombustible residues from the fuel are deposited.

Such a stoker usually provides a flame which tends to concentrate at the rear portion of the furnace because of the downwardly and rearwardly sloping fuel bed and as a result the front part of the furnace combustion space is not utilized efficiently. Moreover in operating a stoker of this type, it is found that the fuel bed will sometimes become too thin in a small localized area. This reduces the resistance to the flow of air through the adjacent tuyère blocks, and the velocity of flow increases considerably. As a result the high velocity air jets pick up small particles of unburned fuel and deposit them in the ash dump where they become mixed with the ashes without further opportunity to be consumed. This greatly reduces the efficiency of combustion.

It is accordingly one object of my invention to overcome these difficulties and to provide a tuyère block for an underfeed stoker which will tend to distribute the flame uniformly throughout the furnace and which will function properly even in areas where the fuel bed is abnormally thin, and have but little tendency to blow unconsumed fuel rearwardly on to the ash dump.

A part of the fuel which is delivered to the furnace of an underfeed stoker usually finds its way downwardly through the openings in the tuyère blocks and into the air chamber between. This fuel is known as "siftings", and causes great inconvenience. It must be removed at intervals, and it sometimes starts to burn in the air chamber, thereby damaging parts of the stoker structure. When the

tuyère blocks are reciprocated, as in certain types of underfeed stokers, there is a tendency to increase the amount of siftings, since the blocks during their rearward movement are thrust directly into the mass of fuel. 55

It is accordingly a further object of the present invention to provide an underfeed tuyère block which will reduce the sifting of fine fuel to a minimum, particularly when used on stokers which are arranged to reciprocate the tuyère blocks. 60

It is a further object of my invention to provide a tuyère block which can be manufactured economically, and which will deliver air to the fuel bed efficiently throughout a long life of usefulness before requiring replacement. 65

With these and other objects in view, as will be apparent to those skilled in the art, my invention resides in the combination of parts set forth in the specification and covered by the claims appended hereto. 70

In accordance with my invention I provide a tuyère block arranged to be mounted on the upper margin of an underfeed retort and shaped to direct jets of air at an angle toward the front of the furnace. Each block preferably comprises a body portion, which may be a flat substantially horizontal plate or web 75 adapted for mounting in step-like formation with other similar blocks. This plate may be provided with air directing ribs. The side of the block preferably slopes away from the retort in a direction toward the rear of the 80 furnace, particularly when it is to be used on a stoker of the type utilizing reciprocating tuyère blocks. 85

Referring to the drawings illustrating one embodiment of my invention and in which like reference numerals indicate like parts. 90

Fig. 1 is a side view of a stoker applied to a furnace, the parts within the furnace being shown in section on the line 1—1 of Fig. 2;

Fig. 2 is a slightly enlarged section of a portion of the stoker on the line 2—2 of Fig. 1; 95

Fig. 3 is an enlarged top plan view of eight tuyère blocks grouped in assembled relationship;

Fig. 4 is a side elevation of the blocks 100

shown in Fig. 3, partially broken away for clearness of illustration;

Fig. 5 is a bottom plan view of four of the blocks shown in Fig. 3;

5 Fig. 6 is a perspective view of a tuyère block, looking at the top thereof; and

Fig. 7 is a perspective view of a tuyère block, looking at the bottom thereof.

In the drawings I have illustrated my invention as applied to an underfeed stoker of the multiple retort type. This comprises a fuel hopper 10 of suitable construction which is mounted outside of and adjacent to the vertical front wall 11 of a furnace. A plurality 15 of horizontal cylindrical ram casings 12 are mounted beneath the hopper and arranged to receive fuel therefrom. A suitable ram, not illustrated, is arranged to be reciprocated within each ram casing by a rotatable crank 20 shaft 14, as is well known in this art. This crank shaft is arranged to be rotated at a slow speed by a suitable gear reduction device 16 which may be driven by any desired source of power. The weight of the casings and 25 associated parts may be supported on pipe columns 17 which rest on a concrete floor 18.

A plurality of parallel underfeed retorts 20 extend rearwardly from the front wall 11. These retorts are provided with stationary 30 bottom plates 21 which incline downwardly at a slight angle toward the rear of the furnace. The sides of the retorts are formed by hollow side bars 24 which are arranged to support on their upper surfaces the tuyère 35 blocks 25. These tuyère blocks are arranged in rows extending longitudinally of the stoker between the retorts and they form a support for the fuel bed and deliver air thereto.

In the embodiment illustrated I have 40 shown these side bars as being suitably constructed for horizontal reciprocation. For this purpose each side bar is supported at its forward end on a cylindrical member 26 which is mounted in a slide bearing 28 forming an integral part of the ram casing. Each side bar is arranged to be reciprocated by its corresponding ram through a lost motion connection 30 in a manner well known in this art and fully disclosed in the patent to Riley 45 No. 1,090,651. At its lower and rearward end each side bar is attached to a shoe 32 arranged to slide over the upper plane surface of a base plate 33 which is bolted to a pair of I-beams 35. These I-beams extend transversely of the stoker and rest in suitable pockets in the side walls of the furnace as will be well understood.

The stoker as illustrated is provided with an overfeed grate section 36. This may be of 50 any suitable construction and is mounted on the side bars 24 beneath the lower end of the retort 20. This overfeed grate serves as a tuyère structure to furnish air for the combustion of any unconsumed coke which issues 55 from the lower end of the underfeed retort.

In the rear of the overfeed grate 36 I have illustrated a rocker dump plate 38, the upper and forward end of which is pivotally connected to the shoe 32. The rocker plates rest at their lower ends on rolls 40 suitably mounted at the rear ends of horizontal rack bars 41. A vertical bridge wall 43 is arranged in the rear of the rocker plates and in substantial proximity thereto. The position of the rocker plates 38 in relation to the bridge wall may be 70 adjusted by means of a horizontal shaft 45 mounted in suitable brackets 46 which are bolted to the forward I-beam 35. This shaft carries a series of pinions 48 which mesh with the teeth on the rack bars. It will be understood that the shaft 45 extends through the side walls of the furnace and is arranged to be controlled from a convenient point.

A vertical plate 50 is mounted beneath the front wall 11 of the furnace so as to entirely enclose a space beneath the stoker retorts and form a pressure chamber 52. Air may be supplied to this pressure chamber from any suitable forced draft apparatus, such as a fan, through a duct 53 which may be provided with a damper 54. Air flows under pressure from the air chamber 52 up through the hollow side bars 24 to the tuyère blocks 25 which deliver it to the fuel bed for combustion.

The present invention is concerned with the construction and arrangement of the tuyère blocks 25. In the preferred embodiment illustrated, each tuyère block comprises a thin elongated flat substantially horizontal plate or web 56 arranged to be mounted in a step-like formation with other similar blocks, as shown particularly in Fig. 4. With this arrangement the major part of each block is covered by the block above, and only the rear or nose portion 57 of the block is exposed on its upper surface to the heat of the fuel bed.

The blocks 25 are arranged to deliver air to the fuel bed for combustion, and they are so shaped as to direct this air in jets at an angle toward the front of the furnace in order to prevent the blowing of fine fuel on to the ash dump. For this purpose I have shown a number of spaced parallel ribs 58 on one face of the web which form air channels terminating at the retort side of the block. In the embodiment illustrated these are located on the lower face of the web 56. These ribs extend inwardly for a substantial distance from the outer edge 60 of the web adjacent to the retort, and they are inclined at an angle toward the front of the furnace, as shown particularly in Figs. 5 and 7. The ribs 58 thus direct jets of air in directions opposed to the rearward movement of the fuel and into the mass of fuel in the retorts 20. The outer edge 60 of the block is shaped to slope away from the retort toward the rear of the furnace, thus reducing the tendency of the rearwardly moving fuel to enter the air openings. With this construction, the front end 125

of the web 56 is wider than the rear end, and the ribs 58 are arranged at an angle extending outwardly and toward the wider end of the web.

5 In order to effectively cool the exposed nose portions 57 of each block, I preferably provide a few additional spaced ribs 61 at the extreme rear end of the block. These ribs may be arranged to direct air rearwardly as shown.

When, as in the embodiment illustrated, the tuyère blocks are to be used on a stoker of the well known Riley type, each block is formed with a straight side edge 63 which at 15 assembly is located parallel to the center line of the retort and in contact with the corresponding portion of the laterally adjacent block, as shown in Fig. 3. As there illustrated, the blocks of adjacent rows are made 20 of opposite hand. In order to prevent air leakage at the joint between tuyère rows, I provide a depending rib 64 extending lengthwise along the edge 63 of each block. This forms an effective seal. A rectangular opening 65 is preferably provided in the forward portion of the web to reduce the resistance to the flow of air through the blocks.

It is desirable that the air jets from the tuyère blocks should issue into the fuel bed 20 at points located materially above the upper margins of the side bars 24. With this arrangement the hot combustion zone is spaced sufficiently from the side bars to avoid danger of burning them. For this purpose, I preferably provide depending vertical plate or flange portions 67 which extend downwardly at each side of the block near the front end thereof and provide an air passage leading to the channels between the ribs 58. The 35 lower edges of these flanges 67 are formed at an angle corresponding to the slope of the side bars 24 on which they rest. The front corners of the blocks are preferably cut out at 68 to form overlapping joints between adjacent blocks, as shown in Fig. 5. This reduces the opportunity for air leakage. The front edges of the flanges 67 are connected by a strengthening plate 69.

40 I prefer to bolt the tuyère blocks 25 in place on the side bars 24, and for this purpose I provide the web 56 of each block with a bolt hole 71 through which a bolt 72 (Fig. 2) may extend. A shallow square recess 73 is shown in the upper surface of the web to receive the head of the bolt. A slightly raised boss 74 may be provided on the lower surface of the web for strengthening purposes. To assist in holding the blocks in proper alignment, I may utilize a lug 75 extending upwardly 45 from each block and in position to contact laterally with the rib 64 on the block above.

The operation of my invention will now be apparent from the above disclosure. Air under pressure from the chamber 52 passes 50 upwardly through the side bars 24 to the

tuyère blocks 25 and into the fuel bed through the channels between the ribs 58. A small part of the air flows between the ribs 61 and thus cools the nose portions 57 of the blocks. The greater part of the air for combustion 70 is directed toward the front of the furnace by the ribs 58. This construction avoids the blowing of fine coal into the ash dump and tends to distribute the flame more uniformly 75 in the furnace chamber. The forwardly directed air jets also penetrate the mass of fuel in the retorts more effectively. The side bars and tuyère blocks are reciprocated to feed the fuel and ash towards the dump plates 38. During the rearward movement of the tuyère 80 blocks, entry of fine fuel into the channels between the ribs 58 is prevented by the angular arrangement of the ribs. These ribs act like plows which crowd the coal away. During the forward movement of the tuyère 85 blocks the air feeding edges 60 of the blocks move away from the packed fuel as a result of their sloping construction. This relieves the pressure and there is but little opportunity for fine fuel to sift through into the air 90 chamber.

Having thus described my invention what I claim as new and desire to secure by Letters Patent is:

1. An underfeed stoker comprising side 95 walls defining a retort through which fuel is moved in a direction lengthwise thereof, and a series of long substantially horizontal tuyère blocks mounted on the upper margins of the walls and arranged in step-like formation, each tuyère block having an edge exposed to the fuel and sloping away from the retort in the direction of fuel movement, and a series of spaced ribs forming air channels terminating at said edge which direct air at 100 an angle opposed to the direction of fuel movement.

2. An underfeed stoker comprising relatively reciprocable side bars forming the 105 walls of adjacent retorts, and a series of long substantially horizontal tuyère blocks mounted on each bar in step-like formation, the adjacent faces of the blocks in the two series being in contact and parallel with the center line of the retort, and the opposite faces of 110 the blocks being exposed towards the retort and sloping away from said center line, each tuyère block having a series of spaced ribs forming channels communicating with the space beneath the blocks and between the side 115 bars which terminate at the exposed faces and slope in a direction opposed to the fuel movement.

3. A tuyère block for a multiple retort underfeed stoker comprising an elongated 120 flat substantially horizontal web having one of its long edges sloping, whereby one end of the web is wider than the other, and a series of spaced ribs on the web which provide 125 air flow channels terminating at the sloping 130

edge and arranged at an angle extending outwardly and toward the wider end of the web.

4. A tuyère block for a multiple retort underfeed stoker comprising an elongated flat substantially horizontal web having one of its long edges sloping, whereby one end of the web is wider than the other, a series of spaced ribs on the web which provide air flow channels terminating at the sloping edge 10 and arranged at an angle extending outwardly and toward the wider end of the web, and depending flanges at the wider end of the web which provide an air passage leading to said channels.

15 5. A tuyère block for an underfeed stoker comprising an elongated flat substantially horizontal web so constructed that it may be piled in step-like formation with the webs of other similar blocks, whereby one end of 20 the web will be exposed, and a series of spaced ribs on the web which provide air flow channels terminating at one of the long edges of the web and arranged at an angle extending outwardly and away from the exposed end 25 of the web.

6. A tuyère structure for an underfeed stoker comprising a series of tuyère blocks arranged in a step-like formation sloping downwardly and rearwardly, each block having 30 means thereon for directing air in jets at an angle laterally and forwardly.

7. An underfeed stoker comprising side walls defining a retort through which fuel is moved in a substantially horizontal direction lengthwise of the retort, and a series 35 of tuyère blocks mounted on the upper margins of the walls, the blocks being shaped to provide air passages which direct air into the retort at an angle opposed to the direction of fuel movement.

8. An underfeed stoker comprising side walls defining a retort through which fuel is moved in a direction lengthwise thereof, and a series of long substantially horizontal 45 tuyère blocks mounted on the upper margins of the walls and arranged in step-like formation, each tuyère block having an edge exposed to the fuel in the retort, and a series 50 of spaced ribs forming air channels terminating at said edge which direct air at an angle opposed to the direction of fuel movement.

Signed at Worcester, Massachusetts, this 55 8th day of December, 1930.

JAMES W. ARMOUR.
